UNITED STATES PATENT OFFICE.

WILLIAM E. WINE, OF TOLEDO, OHIO.

FREIGHT-CAR END.

1,224,344.

Specification of Letters Patent.

Patented May 1, 1917.

Application filed April 3, 1916. Serial No. 88,621.

To all whom it may concern:

Be it known that I, WILLIAM E. WINE, a citizen of the United States, residing at Toledo, in the county of Lucas and the State of Ohio, have invented new and useful Improvements in Freight-Car Ends, of which the following is a specification, reference being had to the accompanying drawings, forming a part hereof.

10 My invention relates to new and useful improvements in freight car construction, and more especially to the construction or formation of metal plates or sections for the end walls thereof.

15 The object of my invention is to provide a steel end for a freight car which is sufficiently strong to withstand the strains of shifting loads within the car as well as that of service conditions from the outside of the car.

20 Another object of my invention is to so form the plates that they will reduce manufacturing costs to a minimum.

25 A still further object of my invention is to so form the plates that they can be readily repaired in any car shop with the present facilities for performing such work.

30 With these and other objects hereinafter explained in view, my invention consists in the construction and combination of elements hereinafter described and claimed.

35 In the accompanying drawings which illustrate the preferred embodiment of my invention; Figure 1 is an elevation of an end of a car provided with steel plates of the construction about to be described and provided with openings for the reception of suitable end windows or ventilators. Fig. 2 is a section on line 2—2 of Fig. 1. Fig. 3 is a section on line 3—3 of Fig. 1. Fig. 4 is a side elevation on the car end. Fig. 5 is a section corresponding to section on line 5—5 of Fig. 1, a solid end car not using end windows and illustrates a modification of the 40 invention as shown in Fig. 2. Fig. 6 is a 45 partial plan view of same, with the roof boards removed. Fig. 7 is a modification of the invention as shown in Fig. 5. Fig. 8 is a section on line 8—8 of Fig. 1.

50 Similar characters designate similar parts throughout the several figures of the drawings.

Referring now to the parts by number, the car end as shown in Fig. 1 is composed of plates, 1, 1^a and 2, provided with flanges 3, 3^a and 4 respectively, which are riveted to

the webs of the Z bar end posts 5. The end posts 5 are attached to the end sill 6 by brackets 7 and spacing angle 8. The end posts 5 are also connected to a horizontal Z bar member 9 by angle brackets 10. The Z bar member 9 is so located that the wood member 9^a rests on top thereof and outside of the inner flange 9^b thus preventing water from entering the car between the Z bar 65 member 9 and the wood member 9^a. The member 9 is connected to the side members 11 by means of gusset plates 12 and bolts 13, thus completing the framing structure to which the end plates 1, 1^a and 2 are attached. The plate 1 is attached to the end sill 6 by rivets 14 along its bottom edge, to end post 5 by means of flange 3 and rivets 15 along its inner edge and to the end plate 9 by flange 16 and rivets 17 along its top 70 edge. The outer edge is provided with a flange 18 which extends around the corner post 19 a sufficient distance to properly reinforce the same and to be securely fastened thereto by means of bolts 20. The end posts 80 5 are provided with wood furring posts 5^a suitable for the reception of the frame of the end windows or ventilators and which also serve as nailing strips for the lining 21 of the car. 85

By flanging the plates 1, 1^a and 2 and riveting them to the webs of the end posts and end plate, a greater strength is obtained for the end, which is not only due to the additional strength of the flanges, but also to the fact that, by the removal of the metal to form the hole in the web, the post is not weakened against lateral bending to any great extent. If these plates were riveted direct to the flanges of the end posts, without flanging the plates, the end posts would be materially reduced in strength and should the car be subjected to great strain either from shifting loads or from outward conditions of service, the posts are liable to become broken at points where such rivet holes have been provided. 95

Referring to the construction shown in all figures including 5, 6 and 7, it will be noted that, should any of the end plates 105 be damaged they can be removed and replaced without entering the car for any purpose whatever, inasmuch as all rivets and bolts can be worked upon from the exterior.

This is most strikingly true with the construction shown in Figs. 5 and 7 which show arrangement of end posts most desirable for 110

box cars not provided with end doors or other ventilating means. In Fig. 5 the end posts 5' are of an I beam construction to which is attached a mailing strip 5": for the reception 5 of the lining 21⁷: Fig. 7 shows the end posts slightly differently arranged so that the inner flanges of the I beam end posts 22 are almost in line with the inner faces of the end plates 23 and 24 and is the construction most 10 desirable where it is not necessary to line the end of the car.

It will be understood from this description that although the improvements of this invention are simple they accomplish in a 15 thoroughly practical manner all the objects sought and that by their employment a car end may be produced which will be simple in manufacture and easily repaired.

It will of course be understood that I do 20 not desire to be limited to the specific construction or arrangement of elements shown and described, as it is obvious that changes in construction and arrangement may be made without departing from the spirit of 25 the invention.

Having thus described my invention, I aim in the appended claims to cover all modifications which do not involve a departure from its spirit and scope.

30 What I claim as new and desire to secure by Letters Patent of the United States is:—

1. In a box car, the ends of which comprise end sills, flanged end posts, transversely extending end members, and vertical 35 sheet metal plates, said transversely extending end members comprising angular metal sections provided with vertical flanges on their inner edges and wood framing members resting thereon and outside of said 40 vertical flanges, said vertical sheet metal

plates having their lower edges secured to said end sills, their vertical edges flanged and secured to the webs of said end posts and their upper edges flanged and secured to the webs of said transversely extending end 45 members.

2. In a box car, the ends of which comprise end sills, corner posts, Z bar end posts, and transversely extending Z bar end members and vertical sheet metal plates, said 50 vertical sheet metal plates having their lower edges secured to said end sills, their inner vertical edges flanged and secured to the webs of said Z bar end posts, their outer vertical edges flanged and secured to said 55 corner posts and their upper edges flanged and secured to the webs of said Z bar end members.

3. In a box car, the ends of which comprise end sills, Z bar end posts, corner 60 posts, transversely extending Z bar end members, outside vertical sheet metal plates and central sheet metal plates, said outside vertical sheet metal plates having their inner edges flanged and secured to the webs of 65 said Z bar end posts, their outer edges flanged and secured to said corner posts, their lower edges secured to said end sills and their upper edges flanged and secured to the webs of said Z bar end members, said 70 central sheet metal plates being flanged at their vertical edges and secured to the webs of said Z bar end posts.

This specification signed and witnessed this 1st day of April, 1916.

W. E. WINE.
